US00D598035S

(12) **United States Design Patent**
Hoshor

(10) **Patent No.:** **US D598,035 S**
(45) **Date of Patent:** **** Aug. 11, 2009**

(54) **APPARATUS FOR SAWING LINEAL MATERIAL TO LENGTH**

(75) Inventor: **Steven T. Hoshor**, Ames, IA (US)

(73) Assignee: **Technical Services, Inc.**, Ames, IA (US)

(**) Term: **14 Years**

(21) Appl. No.: **29/331,177**

(22) Filed: **Jan. 21, 2009**

(51) **LOC (9) Cl. 15-09**

(52) **U.S. Cl. D15/133; D6/492**

(58) **Field of Classification Search** D6/399, D6/400, 421, 422, 426, 429, 480, 483, 484, D6/492; D15/127, 133, 134; 83/432, 435, 83/438, 468, 468.3, 468.7, 471.2, 477, 477.2, 83/478; 144/253.1, 286.1, 286.5, 287

See application file for complete search history.

(57) **CLAIM**

The ornamental design for an apparatus for sawing lineal material to length, substantially as shown and described.

DESCRIPTION

FIG. 1 is a perspective view of the apparatus; and,

FIG. 2 is an end view of the apparatus.

The broken lines in the drawings depict unclaimed environmental subject matter.
